CENTRALIZED TRAFFIC CONTROLLING
SYSTEM FOR RAILROADSSedgwick N. Wight, Rochester, N. Y., assignor to
General Railway Signal Company, Rochester,
N. Y.

Application October 30, 1941, Serial No. 417,134

19 Claims. (Cl. 246—3)

The present invention relates to the remote control of signals on a railway system and to means for indicating when trains pass such signals, and more particularly to means for giving such indications without the employment of the usual detector track circuit.

It is very common practice to have a track circuit known in signal parlance as a "detector track circuit" for indicating when a train passes over the points of a track switch and passes by the signals associated therewith. On many of the railway systems provided with signals which are controlled in accordance with traffic conditions no such detector track circuits are present and one of the principle features of the present invention resides in the provision of circuits and apparatus for manifesting the movement of a train over the switch points of a track switch without the employment of either the usual detector track circuit or the employment of a track instrument. More specifically, it is proposed to manifest such passage of a train over the switch points and to transmit an indication of such movement of the train by the signal to a distant control office by taking into consideration the position the track switch is assuming at the time, the fact whether or not a particular signal is clear, and the fact whether the main track, the passing siding or the first portion of a single track section adjacent such passing siding is then occupied or unoccupied. In other words, it is proposed to take a large number of facts into consideration and to determine from these facts whether or not there is a train moving over the switch points and by such construction avoid the necessity of providing additional insulating joints in the track rails and the additional track battery and track relay which would be necessary if the movement of the train over the switch points were to be ascertained by the employment of a detector track circuit. Another feature of the present invention resides in the provision of means for continuing the indication of a train movement over the switch points, ordinarily known as an OS indication, in the office until it is manually cancelled as, for instance, by the return of a signal control lever to its normal stop position.

Another object of the present invention resides in the provision of novel signals which are normally dark and which if illuminated instruct the train crew to operate the track switch to the side track position and which assume a more favorable aspect in response to operation of said track switch to such side track position.

Other objects, purposes and characteristic features of the present invention will be pointed out in the specification hereinafter and will in part be understood when this specification is read in connection with the attached drawings, of which:

Fig. 1 shows one form of the present invention; and

Fig. 2 shows a modified form of the present invention.

Structure Fig. 1

Referring to Fig. 1 of the drawings the apparatus illustrated in the lower left-hand corner comprises the apparatus located in the central office CO, whereas the apparatus illustrated in the upper right-hand corner is located in the field FS, these apparatuses being connected by line wires 16, 17 and 18, and common return wire C. In the actual track layout including a passing siding PS the track rails have been shown divided into sections by insulating joints 10 of which the section of the side track has been designated 5 and the sections of the main track from left to right have been designated 3, 4, 1 and 2, of which the sections 1 and 4 constitute the main siding section of the passing siding and the sections 2 and 3 each constitute a section of a single track stretch. Additional insulating joints 11 and jumpers 12 are employed to extend the track circuit of the main siding section over the fouling portions of the side track. The left-hand end of the passing siding is provided with a track switch Sw3 and the right-hand end is provided with a track switch Sw1. These track switches may be power operated and controlled from the office, if desired, but in the disclosure illustrated these track switches are presumably operated by hand by a suitable means, not shown, and in accordance with instructions transmitted through the medium of the wayside signals governing traffic onto and off of the main siding section and side track. Each of the sections of main track are track circuited by apparatus including a track battery B and a track relay T, which track batteries and track relays are provided with reference characters having a prefix corresponding to the number of the track section in which they are located. That is, track section 3 is provided with a track battery (not shown) and a track relay 3T, track section 4 is provided with a track battery 4B and a track relay 4T, track section 1 is provided with a track battery 1B and a track relay 1T, and track section 2 is provided with a battery (not illustrated) and a track relay 2T.

Four signals are provided for each track switch to govern the movement of traffic thereover. For the track switch Sw_1 the east-bound signals have been designated S_2 and S_2A for governing traffic off of the main siding section and side track respectively and into the single track section. The signals for governing the movement of traffic over the track switch Sw_1 in a westwardly direction and into the passing siding PS have been designated S_1 for the main siding section and S_1A for the side track. Similarly, the signals for governing east-bound traffic over the track switch Sw_3 have been designated S_4 and S_4A and the signals for governing west-bound traffic over this track switch Sw_3 have been designated S_3 and S_3A . These signals may be of any suitable construction such as semaphore signals, multiple unit light signals, or multiple aspect light signals of the search-light type, having a movable spectacle color screen, but for convenience semaphore signals only have been illustrated for the main siding section and search-light type signals only have been illustrated for the side track. The signals S_1 , S_2 , S_2A , S_3 , S_3A and S_4 are preferably three-position signals indicating green, yellow and red signifying clear, caution and danger, respectively, but for convenience their control circuits have only been shown conventionally to illustrate under what conditions a signal is held at danger or stop and under what conditions it may indicate proceed. Signals S_1A and S_4A are preferably two-position three-condition signals which normally assume the stop position dark condition and which may be operated to the illuminated condition manually from the central office, and which are operated to the proceed position by operation of their associated track switch to the side track position. Since the apparatus at each end of the passing siding is identical the apparatus at the east end of the passing siding only has been shown in considerable detail, the apparatus at the west end having to a large extent been omitted and the control and indication line wires for the west end have, for convenience, been illustrated by a dotted line 15.

The track switch Sw_1 is provided with point detector contacts CSw_1 and CSw_2 , which contacts assume one or the other extreme position when the track switch assumes the corresponding extreme normal or reverse position and is locked, or if desired these contacts CSw_1 and CSw_2 may be the usual switch box contacts which merely manifests the position of the switch. These contacts have been illustrated in their normal main track position. The signals S_1 , S_1A , S_2 and S_2A are controlled by the switch instruction relay SIR_1 and the signal direction relay DRG_1 and also in accordance with the position assumed by the track switch Sw_1 as reflected by the switch box contacts CSw_2 and also, except for signal S_1A , are controlled in accordance with traffic conditions in advance. Some of the control contacts for governing these signals in accordance with traffic conditions in advance have for convenience been omitted. The switch instruction relay SIR_1 is controlled over the line wire 16 and the common return wire C, whereas the signal direction and control relay DRG_1 is controlled over line wire 17 and the same common return wire C.

Referring now to the apparatus in the office, the track layout in the field has been shown in miniature in the office by the conventional showing of a passing siding ps . At the east end of

this miniature passing siding ps has been illustrated a track occupancy indicating lamp OS_1 , a similar lamp OS_3 having been illustrated at the left-hand end of this miniature passing siding ps . These OS lamps OS_1 and OS_3 , which have been provided to manifest track occupancy at the switch points, are respectively lighted when a train moves over the points of the track switches Sw_1 and Sw_3 , and are controlled by the indication relays OSR_1 and OSR_3 , respectively. The switch instruction relay SIR_1 is controlled by the switch instruction lever SIL_1 , the switch instruction lever SIL_3 controlling a similar switch instruction relay not illustrated. The signal lever SGL_3 controls a relay (not shown) similar to signal relay DRG_1 . As conventionally shown the OS indicating relays OSR_1 and OSR_3 are double winding relays of which the upper winding of relay OSR_1 is controlled from the field over the line wire 18 and the lower winding comprises a portion of a stick circuit including the stick contact 30¹ is controlled by the signal lever controlled contact 35¹. The purpose of these indication relays OSR_1 and OSR_3 will be more specifically pointed out in connection with the operation of the system.

Operation Fig. 1

Under normal traffic conditions, that is when there are no trains around and none expected to reach that portion of the railway system, all of the signals will be held at stop manually from the control office CO, the signals S_1A and S_4A being dark signals their lamps being held de-energized manually and the track switches will assume their normal main track position, as illustrated. Under this condition all of the circuits will be deenergized and open except the circuit for the switch instruction relay SIR_1 which will be energized by current of positive polarity and the various track circuits which will be energized and unshunted and their track relays will assume the energized attracted position. Let us now assume that there is a west-bound train moving from right to left somewhere beyond the section 2 in the single track stretch extending eastwardly from the passing siding PS . Let us further assume that the operator in the central office CO desires to clear the signal S_1 at the field station FS to allow the train under consideration to move into the main siding section of the passing siding PS . In order to clear the signal S_1 , assuming clear traffic conditions ahead, for governing west-bound traffic over the main siding sections 1 and 4 the operator will leave the switch instruction lever SIL_1 in its right-hand position to maintain closed the energizing circuit passing from the terminal (+) of the battery BB through the contact of this lever SIL_1 , through line wire 16, through the winding of the switch instruction relay SIR_1 , back through the common return wire C to the mid-point of the battery BB. Also to allow only a west-bound train to move over the track switch Sw_1 the operator will move the direction signal lever DGL_1 to its left-hand position to close an energizing circuit for the direction signal relay DRG_1 which may be traced from the terminal minus (-) of the battery BB through the contact of lever DGL_1 , through line wire 17, through the winding of signal relay DRG_1 , and back over the common return wire C. The closure of these circuits will cause current of positive and negative polarity to flow through the windings of the relays SIR_1 and DRG_1 respectively, thereby causing the polar

contacts of these relays SIR₁ and DRG₁ to be shifted to the right and left, respectively, and will cause the neutral contacts of these relays to assume their raised position. Under this condition of these relays SIR₁ and DRG₁ current may flow from the terminal (+), assuming traffic conditions in two blocks in advance of the signal S₁ to be clear, through wire 19¹, front contact 22¹ of track relay 2T, through the signal mechanism of the signal S₁, through polar contact 23¹ of directional relay DRG₁ assuming its left-hand position, through front contact 24¹ of this same relay, through polar contact 25¹ of switch instruction relay SIR₁ assuming its right-hand position, through front contact 26¹ of this same relay, and through switch box contact CSw₂ assuming its main track position, to the common return wire C connected to the mid-point of the field battery. If the block in advance of the signal S₃ had been occupied then traffic conditions in advance of the signal S₁ would have reflected caution traffic conditions and the signal S₁ would have assumed its caution position, in which position the signal contact C₁ assumes its intermediate position and is also closed.

Let us now assume that the west-bound train enters upon the track section 2 and causes deenergization of the track relay 2T. This produces no immediate result, for even though it closes its back contact 32¹ this contact is included in otherwise open circuits and produces no current flow. Let us now assume that the west-bound train passes the clear signal S₁ and treads upon the track circuit including the track relay 1T, which occurs when the west-bound train passes over the points of the track switch Sw₁. This causes deenergization of the track relay 1T and the closure of its back contact 29¹. With the back contact 29¹ closed and with the contact blade C₁ assuming either the clear or the caution position an energizing circuit for the upper winding of the indication relay OSR₁ may be traced as follows: beginning at the terminal plus (+) of the battery BB, contact 35¹ of the signal lever DGL₁ assuming its left-hand position, the upper winding of the relay OSR₁, back contact 29¹ of track relay 1T, signal contact C₁ of the signal S₁ assuming its clear or caution position, and over the common return wire C and to the mid-point of the battery BB. This circuit is only momentarily closed because the dropping of the track relay 1T causes the signal S₁ to be operated to its stop position by the opening of front contact 22¹ of the track relay 1T. During this momentary closure of the circuit for the upper winding of the relay OSR₁, just traced, this indication relay OSR₁ will be operated to its energized position and will then be maintained energized through a stick circuit including the contact 35¹ of the signal lever DGL₁ and the stick contact 38¹ of this relay OSR₁, so that this relay will remain energized until its stick circuit has been broken by manual movement of the lever DGL₁. With the indication relay OSR₁ energized and its front contact 37¹ closed the indicating lamp OS₁ at the east end of the miniature track layout is energized and illuminated and manifests to the operator that the west-bound train has moved over the points of the track switch Sw₁. As soon as the operator has been informed of the movement of the west-bound train over the points of the track switch Sw₁ he will return his signal lever DGL₁ to its normal middle position which causes the interruption of the stick circuit for the relay OSR₁ by the opening of contact 35¹ of the

signal lever DGL₁ and will cause deenergization of the signal relay DRG₁. The breaking of this stick circuit for the relay OSR₁ will, of course, cause this relay to assume its deenergized retracted position in which position the front contact 37¹ of this relay is open.

Let us now assume that all of the apparatus has been returned to its normal condition and that a similar west-bound train is now approaching and that the operator desires this train to move into the side track 5 of the passing siding PS. In order to accomplish this the operator will operate his direction signal lever DGL₁ to the left, signifying that west-bound traffic is to move over the track switch Sw₁, and which results in energization of the signal relay DRG₁ to its left-hand position. The operator will simultaneously operate his switch instruction lever SIL₁ to the left-hand position which signifies the reverse position for the switch and results in energization of the switch instruction relay SIR₁ to its left-hand energized position. With both of the relays SIR₁ and DRG₁ energized to the left an energizing circuit for the lamp in the search-light signal S_{1A} is closed which may be traced as follows: beginning at the terminal (+) of a suitable source of current located at the field station, front contact 40¹ of the relay SIR₁, polar contact 41¹ of this same relay assuming its left-hand position, front contact 42¹ of the relay DRG₁, and polar contact 43¹ of this same relay assuming its left-hand position through the lamp of the signal S_{1A} to the other terminal (-) of said source of current. The normally dark signal S_{1A} is now lighted and displays by a color, such as red, the letter S instructing the train crew to operate the track switch Sw₁ to its reverse position. As soon as this track switch has been reversed and the switch box contact CSw₂ has been moved to its lower position a circuit for the mechanism of the signal S_{1A}, which may be traced as follows, is closed: beginning at the terminal (+), the mechanism of signal S_{1A}, polar contact 45¹ of the relay DRG₁ assuming its left-hand position, neutral contact 46¹ of this same relay, switch box contact CSw₂ to the other terminal (C) of this same source of current. The flow of current in this circuit will operate the mechanism of the signal S_{1A} to its proceed position causing it to emit a proceed light beam, such as yellow, informing the engineer that he may move his train into the siding 5.

Let us now observe how the movement of the train into the side track is indicated in the central office. With the track switch assuming its reverse position the switch box contact CSw₁ is closed. Movement of the west-bound train in the section 2 will, of course, cause deenergization of the track relay 2T and closure of its back contact 32¹. The closure of this contact 32¹ prepares a circuit which will be traced hereinafter. As the train progresses westward and passes the insulating joints 10 at the signal S_{1A} the track relay 1T is deenergized causing closure of its back contact 29¹ unless it was already closed by a train on the main track. If there was a waiting east-bound train on the main siding section the closure of the prepared circuit took place when the track switch Sw₁ was operated to the take-siding position by the train crew of the west-bound train. This closure of the last of the three contacts 29¹, CSw₁ and 32¹ results in closure of the prepared circuit heretofore mentioned, which may be traced as follows: starting at the terminal (+) of the battery BB, contact 35¹ of the lever

DGL₁ assuming its left-hand position, upper winding of the indicating relay OSR₁, line wire 18, back contact 29¹ of the track relay 1T, switch box contact CSw₁, back contact 32¹ of the track relay 2T, to the common return wire C connected to the mid-point of the battery BB. The completion of this circuit will, of course, cause energization of the indicating relay OSR₁, which relay will then remain energized through a stick circuit including its stick contact 30¹. As soon as the train has fully entered the side track 5 the operator may extinguish the indicating lamp OS₁ by returning the signal lever DGL₁ to its middle normal position. The operator will, of course, also return his switch instruction lever SIL₁ to its normal right-hand position as soon as he is informed that the train has passed the take-siding signal S₁A, and the train crew will have standing instructions to always return the track switch to the normal main track position as soon as a train which passed into or out of the side track has completed its movement.

Let us now assume that there is an east-bound train moving in the main siding section 4 of the passing siding PS and that the operator wishes this train to continue its movement into the single track stretch including the main track section 2. In order to allow the movement of the east-bound train into the section 2 the operator in the central office will leave the switch instruction lever SIL₁ in its right-hand position and will move the signal lever DGL₁ into its right-hand position, signifying east-bound traffic. With both of these levers assuming the right-hand positions the relays SIR₁ and DRG₁ at the field station will assume their right-hand energized position. With the relays SIR₁ and DRG₁ both energized to the right and with the track switch Sw₁ returned to its main track position, a proceed circuit for the signal S₂ is closed which may be traced as follows: beginning at the line wire 59¹ which is controlled in accordance with traffic conditions in advance and is connected to either the plus (+) or the minus (-) terminal of the field battery depending upon whether traffic conditions in advance of the signal S₂ are clear or caution respectively, through the front contact 51¹ of the track relay 2T, through the mechanism of the signal S₂, through polar contact 23¹ of relay DRG₁ assuming its right-hand position, through the neutral contact 24¹ of this same relay, through polar contact 25¹ of the relay SIR₁ assuming its right-hand position, through neutral front contact 26¹ of the relay SIR₁, through switch box contact CSw₂, to the common return wire C, connected to the mid-point of said field battery. The east-bound train may now proceed into the section 2 at either high speed or at caution speed depending upon whether the signal S₂ is indicating clear or caution which depends on traffic conditions in advance.

Let us now observe how the operator in the central office is informed of the movement of the east-bound train over the points of the track switch Sw₁. As the east-bound train passes over the insulating joints 10 adjacent the track battery 1B, the track relay 1T is deenergized causing closure of its back contacts 29¹. The closure of contacts 29¹ will prepare a circuit for the indication relay OSR₁ which circuit is still open at another point and which will be traced hereinafter. It should be observed that since the signal S₂ is in either its clear or its caution position its semaphore contact C2 is closed which

prepares said circuit at another point. As the east-bound train now passes the signal S₂, this signal indicating either clear or caution, the track relay 2T is deenergized causing closure of its back contact 32¹ which results in closure of the following circuit: beginning at the terminal (+) of the battery BB in the central office, contact 35¹ of the lever DGL₁ assuming its right-hand position, upper winding of the indicating relay OSR₁, line wire 18, back contact 29¹ of track relay 1T, semaphore contact C2 of the signal S₂, back contact 32¹ of the track relay 2T, to the common return wire C connected to the mid-point of the battery BB. The closure of this circuit will of course result in the energization of the indicating relay OSR₁ and in the illumination of the indicating lamp OS₁. Shortly after deenergization of the track relay 2T the circuit for the upper winding of the indicating relay OSR₁ will be broken at the semaphore contact C2 of the signal S₂. This will, however, not cause deenergization of the indicating relay OSR₁ because this relay is held up through its stick circuit including the stick contact 30¹. As soon as the operator has been informed of the movement of the train past the signal S₂ he will return his signal lever DGL₁ to its middle position thereby causing deenergization of the signal relay DRG₁ and extinguishment of the indicating lamp OS₁ so that the signal S₂ will not be returned to proceed when the east-bound train gets beyond the control track circuits for the signal S₂. The operator in the central office is therefore informed of the movement of the east-bound train over the switch points of the track switch Sw₁.

Let us now assume that there is an east-bound train standing on the section 5 of the side track of the passing siding PS and that the operator wishes this train to proceed into the single track section 2. In order to accomplish such movement of the east-bound train the operator will move his switch instruction lever SIL₁ to its left-hand position and move his signal direction lever DGL₁ to its right-hand position, which will cause the relays SIR₁ and DRG₁ at the field station to assume their left-hand energized position and their right-hand energized position, respectively. It should be remembered that the signal S₂A is normally a dark signal which signifies to the train crew that they may not operate the track switch to the reverse position. With the relays SIR₁ and DRG₁ energized to the left and to the right, respectively, the following circuit for the lamp in the signal S₂A is closed: starting at the terminal (+) of the field battery, front contact 49¹ of the relay SIR₁, polar contact 41¹ of this same relay assuming its left-hand position, front contact 42¹ of the relay DRG₁, contact 43¹ of this same relay assuming its right-hand position, the search-light lamp for the signal S₂A to the other terminal (-) of the field battery. The illumination of this signal S₂A will display in the red the letter S which instructs the train crew to operate the track switch Sw₁ to its reverse position. As soon as manual operation of the switch Sw₁ to its reverse position has been completed and the switch box contact CSw₂ has been operated to its lower position the following circuit for the mechanism of the signal S₂A is closed: beginning at the terminal (+) or (-) of the field battery, depending upon traffic conditions in advance, line wire 50¹, front contact 51¹ of the track relay 2T, mechanism of the signal S₂A, polar contact

45¹ of the relay DRG1 assuming its right-hand position, neutral contact 46¹ of this same relay and switch box contact CSw2 assuming its side track or lower position to the common return wire C connected to the mid-point of the field battery (not shown). The signal S2A will now indicate either clear or caution (green or yellow) depending on traffic conditions in advance and the east-bound train may move off of the side track 5 and into the single track stretch 2 in response to the proceed indication of the signal S2A.

Let us now observe how the operator in the central office is informed of this movement of the east-bound train off of the side track and into the track stretch 2. As the train passes over the insulating joints 10 at the east end of the track section 5 of the side track it causes shunting and deenergization of the track relay 1T which causes closure of back contact 29¹ of this track relay. This prepares a circuit for the indicating relay OSR1 which circuit will be traced when closed. As the east-bound train now proceeds over the track switch Sw1, and assuming traffic conditions in advance to be clear, as it passes the insulating joints 10 adjacent the signal S2A it will cause shunting and deenergization of the track relay 2T. This results in closure of back contact 32¹ of this track relay and closure of the prepared energizing circuit for the indicating relay OSR1 which may be traced as follows: starting at the terminal (+) of the battery BB, contact 35¹ of the lever DGL1 assuming its right-hand position, upper winding of the indicating relay OSR1, line wire 18, back contact 29¹ of the track relay 1T, switch box contact CSw1, back contact 32¹ of the track relay 2T to the common return wire C connected to the mid-point of the battery BB. The closure of this circuit will of course result in the energization of the indicating relay OSR1, which relay upon assuming its energized position will close the stick circuit including the stick contact 30¹. The indicating lamp OS1 is of course now energized and informs the operator that the east-bound train has proceeded into the single track section 2. The operator may now return his signal lever DGL1 to its middle position and the switch instruction lever SIL1 to its normal right-hand position so that the signal S2A will again become a dark signal to prevent a second train following the east-bound train just considered. The train crew will of course return the track switch Sw1 to its normal main track position in accordance with standing instructions.

It is of course understood that the method of transmitting controls and indications to and from the field station with respect to the office depends on local conditions and it should be understood that a code type centralized traffic controlling system such as shown in the patent to Hailes and Brixner No. 2,259,561 granted October 21, 1941, may be used instead of the unit line wire construction shown, if desired.

Structure of Fig. 2

In Fig. 2 of the drawings has been illustrated a modified form of the present invention. It will be observed that in the structure of Fig. 1 the main siding section of the passing siding PS is provided with insulating joints 10 near the mid-point of this main siding section, whereas in Fig. 2 a center fed track circuit including only a battery 4B—1B connected across the mid-point of this main track is shown. In other words, in

the Fig. 2 structure the additional insulating joints at the mid-point of the main track have been dispensed with. In the Fig. 2 structure there is a bare possibility that the track relay 1T may be deenergized when a west-bound train moves off of the side track 5 and into the fouling section. If it were the case a false indication might be given if the indicating apparatus illustrated in Fig. 1 were employed. For this reason a directional stick relay SR2 having a back contact 55 included in series with the switch box contact CSw1 is employed in the Fig. 2 structure. Aside from the differences just mentioned, and the provision of circuits for the directional stick relay SR2, the structures of Fig. 1 and Fig. 2 are identical, and therefore like parts and devices have been designated by like reference characters.

The stick relay SR2 is provided with a pick-up circuit which may be traced from the terminal plus (+) of the field battery, back contact 56¹ of the track relay 1T, back contact 57¹ of the track relay 2T, semaphore contacts C2 or C2A depending upon whether the signal S2 or the signal S2A is assuming a proceed position and winding of the stick relay SR2 and back to the other terminal (—) of the field battery. The stick circuit for this directional stick relay SR2 may be traced from a terminal plus (+), through back contact 58¹ of the track relay 2T and stick contact 59¹ of the stick relay SR2, through its winding and to the terminal minus (—).

It will be readily observed that if an east-bound train which just passed off of the side track 5 over the fouling section and into the single track section 2 should still be standing on the track section 2 and hold the track relay 2T de-energized, and also assuming that the train crew has not yet, possibly for lack of time, returned the track switch Sw1 to its main track position the de-energization of the track relay 1T by the movement of either a west-bound train off of the siding or an east-bound train moving off of the track section 3 and over the track switch Sw3, which might possibly cause deenergization of the track relay 1T, that no movement of the train over the switch points of switch Sw1 will be indicated in the central office by illumination of the indicating lamp OS1 in the Fig. 2 structure even if the track relay 1T did drop, because the energizing circuit for the indicating relay OSR1, which otherwise would have been completed, will not be completed by reason of the open back contact 55 of the directional stick relay SR2. In order to get a more clear understanding of this feature of the modification illustrated in Fig. 2 a few train operations will be considered.

Let us assume that there is an east-bound train at the east end of section 5 of the side track of passing siding PS and that there is also a west-bound train on the west end of this section 5 which could, for instance, be a work train which backed into this section. As the crew of the east-bound train in response to the appearance of the letter S on the signal S2A operates the track switch Sw1 to the reverse position the switch box contact CSw1 is closed, it being of course understood that the operator has operated his levers SIL1 and DGL1 to the left and right, respectively. This will of course cause the signal S1A to display a color beam signifying either caution or clear depending on traffic conditions in advance. Let us assume that the east-bound train in response to this signal indication moves into the track section 2 as would ordinarily be the

case. This will cause dropping of the track relay 1T followed by dropping of the track relay 2T and since the switch box contact CSw¹ and the back contact 55 of the directional stick relay SR2 (see Fig. 2) are now closed a pick-up circuit for the indicating relay OSR¹ is completed which is readily traced in the drawings. This will cause the illumination of the indicating lamp OS¹ in the central office to inform the operator that the east-bound train has moved off of the side track and out of the passing siding PS. It is of course understood that movement of the east-bound train out of the passing siding PS will result in the energization of the directional stick relay SR2 after the indicating relay OSR¹ was energized. This energization of the directional stick relay SR2 is somewhat delayed because this relay SR2 is slow acting, this directional stick relay SR2 being picked up through its pick-up circuit closed while the track relays 1T and 2T are deenergized and so long as the contact C2A of the signal S2A remains closed. The directional stick relay SR2 when once up is of course stuck up through a stick circuit including the back contact 58¹ of the track relay 2T and remains stuck up so long as the east-bound train is in the track section 2.

Let us now assume that the operator returns his signal lever DGL¹ back to its normal and middle position resulting in the extinguishment of the indicating lamp OS¹ and for some reason or other, as for instance in order to set up a signal indication for the east-bound train to make a back-up move into the main siding section of the passing siding PS, returns the lever DGL¹ to either extreme position. Let us assume that the train crew has not yet had time to return the track switch Sw¹ to its normal main track position. If now the west-bound train moves off of the passing siding PS and into the single track section 3 and if such movement results in the deenergization of the track relay 1T, this movement of the west-bound train will not cause an indication to be given reflecting the movement of a train over the switch points at the east end of the passing siding PS, because the back contact 55 of the directional stick relay SR2 is now open. In other words, even though a center fed track circuit is employed on the main siding section of the passing siding PS having a track relay at each end thereof and of such construction that both track relays are deenergized if a train enters either end of the track circuit the indications of train movement over the points of a track switch will only be given for that end at which a train actually passes over the points of the track switch.

The applicant has thus provided a rather simple centralized traffic controlling system together with means for positively instructing the train crew to operate a track switch by hand and has further provided means for indicating the movement of a train over the points of a track switch without the employment of the usual detector track circuit and its additional track battery, track relay and insulating joints.

Having thus shown and described several specific embodiments of applicant's invention it is desired to be understood that these embodiments have been selected for the purpose of disclosing the nature of the invention and the functions which it performs and it is desired to be understood that various modifications, changes and additions may be made to adapt the invention to the particular problem encountered in practic-

ing the same as, for instance, by the employment of a code type communicating system instead of a unit line wire control and indication system, without departing from the spirit or scope of the invention except as demanded by the scope of the following claims.

What I claim as new is:

1. In combination with a railway track including a passing siding consisting of a side track and a main siding section adjacent thereto and connected to two single track stretches by two track switches; signals associated with each of said track switches for governing the movement of traffic in both directions over such track switches; a first track circuit including a source of current and a track relay for the main siding section and extending from one pair of switch points to the other pair of switch points of said track switches; a track circuit including a track relay for an adjacent section of each of said single track stretches; and means for each track switch controlled by contacts reflecting the conditions of said first track circuit, by contacts of the track relay for the adjacent track section of the adjacent single track stretch, by contacts of the adjacent track switch and by contacts of the signals associated therewith, for manifesting when a train moves over such particular track switch.

2. In combination with a railway track including a passing siding consisting of a side track and a main siding section arranged side by side and connected to two single track stretches by two track switches; signals associated with one of said track switches for governing the movement of traffic in both directions over such track switch; a first track circuit including a source of current and a track relay for and extending substantially half the length of the main siding section; a second track circuit including a source of current and a track relay for an adjacent section of the single track stretch associated with said one track switch; and means controlled by contacts reflecting the conditions of the two track relays, said one track switch and certain of the signals associated with said one track switch for manifesting when a train moves over said one track switch.

3. In combination with a railway track including a passing siding consisting of a side track and a main siding section adjacent thereto connected to two single track stretches by two track switches; signals associated with each of said track switches for governing the movement of traffic in both directions over such track switches, a center fed main siding section track circuit including a source of current connected across the rails near the middle of the main siding section and a track relay at each end of said main siding section; a track circuit including a track relay for an adjacent section of each of said single track stretches; and means for each track switch controlled by contacts of such track switch, by contacts reflecting the conditions of the track relays adjacent that track switch and by contacts controlled by the adjacent signals, for manifesting when a train moves over that particular track switch.

4. In combination with a railway track including a passing siding consisting of a main siding section and a side track in multiple connected to two single track stretches by track switches; signals associated with one of said track switches for governing the movement of traffic in both directions over such track switch; a first track

circuit including a source of current connected across the rails near a mid-point of said main siding section and a track relay near said one track switch; a track circuit including a source of current and a track relay for an adjacent section of the single track stretch associated with said one track switch; and means controlled by contacts reflecting the conditions of the two track relays, said one track switch and certain of the signals associated with said one track switch for manifesting when a train moves over said one track switch.

5. In combination with a railway track including a passing siding consisting of a main siding and a side track in multiple therewith connected to two single track stretches by track switches; signals associated with one of said track switches for governing the movement of traffic in both directions over such track switch; insulating joints near the middle of said main siding to divide it into two siding sections; a first track circuit including a source of current connected across the track rails near said insulating joints but in a direction toward one of said track switches and a track relay connected across the track rails of the main siding section adjacent said one track switch; a track circuit including a source of current and a track relay for an adjacent section of the single track stretch associated with said one track switch; and means controlled by contacts reflecting the conditions of the two track relays, said one track switch and certain of said signals associated with said one track switch for manifesting when a train moves over said one track switch.

6. In combination with a railway track including a passing siding consisting of a main siding and a side track in multiple therewith connected to two single track stretches by track switches; signals associated with one of said track switches for governing the movement of traffic in both directions over such track switch; insulating joints near the middle of said main siding for dividing it into two siding sections; a first track circuit including a source of current connected across the track rails near said insulating joints but in a direction toward one of said track switches and a track relay connected across the track rails of the main siding section adjacent said one track switch; a track circuit including a source of current and a track relay for an adjacent section of the single track stretch associated with said one track switch; and means controlled by contacts reflecting the conditions of the two track relays, the position assumed by said one track switch and the conditions of certain of said signals associated with said one track switch for momentarily closing a circuit to momentarily manifest the movement of a train over said one track switch.

7. In combination with a railway track including a passing siding consisting of a side track and a main siding section adjacent thereto and connected to two single track stretches by two track switches; signals associated with each of said track switches for governing the movement of traffic in both directions over such track switches; a first track circuit including a source of current and track relay means for the main siding section and extending from one pair of switch points to the other pair of switch points of said track switches; a track circuit including a track relay for an adjacent section of each of said single track stretches; and means for each track switch including a stick relay and including contacts

reflecting the positions of the associated track switch, the conditions of the adjacent track relays, the condition of said track relay means, and the conditions of the signals adjacent such track switch for manifesting when a train moves over such particular track switch.

8. In combination with a railway track including a passing siding consisting of a main siding section and a side track arranged in multiple and connected to two single track stretches by two track switches; signals associated with each of said track switches for governing the movement of traffic in both directions over such track switches; a center fed main track circuit including a source of current connected across the track rails near the middle of the main siding section and a track relay at each end of said main siding section; a second track circuit including a track relay for an adjacent section of each of said single track stretches; and means for each track switch including a stick relay and including contacts reflecting the positions of the associated track switch, contacts reflecting the conditions of the adjacent track relays and contacts reflecting the conditions of the signals associated with that track switch, for manifesting when a train moves over the points of such particular switch.

9. In combination with a railway track including a passing siding consisting of a main siding section and a side track arranged in multiple and connected to two single track stretches by two track switches; signals associated with each of said track switches for governing the movement of traffic in both directions over such track switches; a first track circuit including a source of current and a track relay for the main siding section and extending from one pair of switch points to the other pair of switch points of said track switches; a second track circuit including a track relay for an adjacent section of each of said single track stretches; a stick relay having a pick-up circuit closed momentarily as a train moves over one of said track switches in a direction into the adjacent single track stretch and having a stick circuit including a back contact of the track relay of the said adjacent section of said adjacent single track stretch; and means including said stick relay and also including contacts reflecting the positions of said one track switch and the conditions of the signals and track relays adjacent to said one track switch for manifesting when a train moves over said particular track switch.

10. In combination with a railway track including a passing siding consisting of a main siding section and a side track arranged in multiple therewith and connected to two single track stretches by track switches; signals associated with one of said track switches for governing the movement of traffic in both directions over such track switch; a first track circuit including a source of current and a track relay for the main siding section; a second track circuit including a source of current and a track relay for an adjacent section of the single track stretch associated with said one track switch; and circuit means including three circuits for manifesting the movement of a train over said one track switch of which the first includes contacts closed when the signal governing traffic in one direction over said one track switch in its normal position indicates clear and the track relay for the main siding section assumes its de-energized position, of which the second circuit

includes contacts closed when the signal for governing traffic in the opposite direction over said one track switch in its normal position indicates clear and both the track relay for the main track and the siding section relay for an adjacent section of the adjacent single track stretch assume their deenergized position, and the third circuit of which includes contacts closed when said one track switch assumes its reversed position and both the track relay for the main siding section and the track relay for said adjacent section of said adjacent single track stretch assume their deenergized position.

11. In combination with a railway track including a passing siding consisting of a main siding section and a side track arranged in multiple therewith and connected to two single track stretches by track switches; signals associated with one of said track switches for governing the movement of traffic in both directions over such track switch; a first track circuit including a source of current and a track relay for the main siding section; a second track circuit including a source of current and a track relay for an adjacent section of the single track stretch adjacent said one track switch; circuit means including three circuits for manifesting the movement of a train over said one track switch of which the first includes contacts closed when the signal governing traffic in one direction over said one track switch in its normal position indicates clear and the track relay for the main siding section assumes its deenergized position, of which the second circuit includes contacts closed when the signal for governing traffic in the opposite direction over said one track switch in its normal position indicates clear and both the track relay for the main siding section and the track relay for an adjacent section of the adjacent single track stretch assume their deenergized position, and the third circuit of which includes contacts closed when said one track switch assumes its reversed position and both the track relay for the main siding section and the track relay for said adjacent section of said adjacent single track stretch assume their deenergized position; a local control office; line circuits connecting said office and said one track switch; means at said control office for controlling said signals over said line circuits; and indication means at said office controlled by said circuit means and over said line circuits.

12. In combination with a railway track including a passing siding consisting of a main siding section and a side track arranged side by side and connected to two single track stretches by two track switches; signals associated with each of said track switches for governing the movement of traffic in both directions over such track switches; a first track circuit including a source of current and a track relay for the main siding section and extending from one pair of switch points to the other pair of switch points of said track switches; a track circuit including a second track relay for an adjacent section of each of said single track stretches; a stick relay for each track switch having a pick-up circuit closed when a train moves over the associated track switch in a direction toward the adjacent single track stretch and having a stick circuit including a contact closed so long as said adjacent section of said adjacent single track stretch is occupied; and circuit means including three circuits for each track switch for manifesting the movement of a train over such track switch of

which the first includes contacts closed when the signal governing traffic in one direction over said one track switch in its normal position indicates clear and the track relay for the main siding section assumes its deenergized position, of which the second circuit includes contacts closed when the signal for governing traffic in the opposite direction over such track switch in the normal position indicates clear and both the track relay for the main siding section and the track relay for an adjacent section of the adjacent single track stretch assume their deenergized position, and the third circuit of which includes contacts closed when such track switch assumes its reversed position, said stick relay assumes its energized position, and both the track relay for the main siding section and the track relay for said adjacent section of said adjacent single track stretch assume their deenergized position.

13. In combination with a railway track including a passing siding consisting of a main siding section and a side track connected to two single track stretches by two track switches; signals associated with each of said track switches for governing the movement of traffic in both directions over such track switches; a first track circuit including a source of current and a track relay for the main siding section and extending from one pair of switch points to the other pair of switch points of said track switches; a track circuit including a second track relay for an adjacent section of each of said single track stretches; a stick relay for each track switch and having a pick-up circuit closed when a train moves over the associated track switch in a direction toward the adjacent single track stretch and having a stick circuit including a contact of the track relay of the track circuit of said adjacent section of said adjacent single track stretch; circuit means including three circuits for each track switch for manifesting the movement of a train over such track switch of which the first includes contacts closed when the signal governing traffic in one direction over said one track switch in its normal position indicates clear and the track relay for the main siding section assumes its deenergized position, of which the second circuit includes contacts closed when the signal for governing traffic in the opposite direction over such track switch in the normal position indicates clear and both the track relay for the main siding section and the track relay for an adjacent section of the adjacent single track stretch assume their deenergized position; a local office; line circuits connecting said office and such track switch; means at said control office for controlling said signals over said line circuits; and indication means at said office controlled by said circuit means and over said line circuits.

14. In combination with a railway track including a passing siding consisting of a main siding section and a side track connected to two single track stretches by two track switches; signals associated with each of said track switches for governing the movement of traffic in both directions over such track switches; a first track circuit including a source of current and a track relay for the main siding section and extending from one pair of switch points to the other pair of switch points of said track switches; a track circuit including a second track relay for an adjacent section of each of said single track stretches; a stick relay for each track switch having a pick-up circuit closed when a train moves over the associated track switch in a direction toward the adjacent single track stretch and having a stick circuit including a contact closed so long as said adjacent section of said adjacent single track stretch is occupied; and circuit means including three circuits for each track switch for manifesting the movement of a train over such track switch of

from one pair of switch points to the other pair of switch points of said track switches; a track circuit including a track relay for an adjacent section of each of said single track stretches; a stick relay having a pick-up circuit closed momentarily as a train moves over one of said track switches in a direction into the adjacent single track stretch and having a stick circuit including a back contact of the track relay of the track circuit of said adjacent section of said adjacent single track stretch; and means including said stick relay and also including contacts reflecting the positions of said one track switch and the conditions of the signals and track relays adjacent to said one track switch for manifesting when a train moves over said particular track switch.

15. In combination; a track switch connecting either a main siding section or a side track to a single track switch, a signal for governing traffic off of the side track into the single track stretch including a movable color screen, a cover glass having operating instructions thereon which are visible only when light is emitted from said cover glass and an electric incandescent lamp back of said color screen and cover glass and giving instructions to operate said track switch to the side-track position; a central office remote from said track switch; an electro-responsive device for governing the operation of said color screen in accordance with traffic conditions in advance and displaying a danger indication when said electro-responsive device assumes the deenergized position; control means including a control circuit extending from said office to said track switch for governing the illumination of said lamp; and contacts in the control circuit of said electro-responsive device closed only when said track assumes the side track position; whereby upon illumination of said lamp by an operator at said office when said track switch assumes the main position causes said signal to indicate danger and display said instructions to operate the track switch to the side track position and whereby upon operation of said track switch to the side track position said signal assumes a more favorable position if traffic conditions in advance are favorable.

16. In combination, a track switch for connecting the main siding section or the side track of a passing siding to a single track stretch, a multiple aspect signal for instructing the train crew to operate said track switch to the side track position and to govern the movement of traffic off of said side track and into said single track stretch in accordance with conditions of traffic in said single track stretch, a central office, a line circuit extending from said office to said track switch, means including said line circuit for controlling said signal by energizing said line circuit from said central office to display an aspect instructing the train crew to operate said track switch from its main siding position to its side track position, and means for causing said signal to display a proceed aspect effective only if said line circuit is energized and said track switch assumes the side track position.

17. In combination, a track switch for connecting the main siding section or the side track of a passing siding to a single track stretch, a multiple aspect signal for instructing the train crew to operate said track switch to the side track position and to govern the movement of traffic off of said side track and into said single track stretch in accordance with conditions of traffic in said single track stretch, a central office, a line circuit extending from said office to said track switch, means including said line circuit for controlling said signal by energizing said line circuit from said control office to display an aspect instructing the train crew to operate said track switch from its main siding position to its side track position, and means for causing said signal to display a proceed aspect effective only if said line circuit is energized, traffic conditions in said single track stretch are favorable and said track switch assumes the side track position.

18. In combination, a track switch for connecting the main siding section or the side track of a passing siding to a single track stretch, a multiple aspect take-siding signal for instructing the train crew to operate said track switch to the side track position and to govern the movement of traffic off of said single track stretch and into the side track of said passing siding, a central office, a line circuit extending from said office to said track switch, means for controlling said take-siding signal through the medium of said line circuit from said central office to display an aspect instructing the train crew to operate said track switch from its main siding position to its side track position, and means for causing said signal to display a proceed aspect effective only if said line circuit is energized and said track switch assumes the side track position.

19. In combination, a track switch for connecting the main siding section or the side track of a passing siding to a single track stretch, a multiple aspect take-siding signal including a movable spectacle multi-color screen and an electro-responsive device for operating said spectacle and a normally extinguished electric lamp back of said screen for instructing the train crew to operate said track switch to the side track position by the illumination of said lamp and to govern the movement of traffic off of said single track section and into the side track of said passing siding in accordance with the position assumed by said spectacle, a central office, a line circuit extending from said office to said track switch, means partly in said office and partly at said track switch for illuminating the lamp of said take-siding signal by energizing said line circuit to display an aspect instructing the train crew to operate said track switch from its main siding position to its side track position, and means for controlling said electro-responsive device to display a proceed aspect effective only if said line circuit is energized and said track switch assumes the side track position.
